UNITED STATES PATENT OFFICE.

CHARLES B. LAWTON, OF DETROIT, MICHIGAN.

STALL FOR BUILDINGS.

Application filed March 3, 1927. Serial No. 172,306.

This invention relates to stalls or compartments for buildings and has special reference to stalls that may be used for the storage or safe keeping of automobiles and other types of vehicles, and various kinds of merchandise, the stalls being especially designed for garages, terminals, piers and such other parking places where vehicles may be stored or temporarily placed for the safe keeping of any merchandise on the vehicles.

My invention, in its broadest aspect, involves a row of angularly disposed stalls, the stalls being so disposed at such angles as to occupy minimum space and facilitate the movement of vehicles into and out of the stalls. It is in this connection that the stalls may be advantageously used in a garage or parking building with run-ways or aisles between the rows of stalls, and with the stalls disposed at a right angle to one another and at less than a right angle to a runway or aisle, the run-ways or aisles may be of minimum width, at least narrower than usual because a vehicle may be driven direct into or out of a stall, without any great turning or manipulation in the runways or aisles. Ordinarily a stall is placed at a right angle to an aisle or drive-way and if the aisle or driveway is narrow it is impossible to enter the stall or drive therefrom without manipulating the vehicle in the driveway or aisle. Consequently driveways and aisles are often made wide and occupy considerable space in a building or part thereof, which space can be saved by placing the stalls at an obtuse angle to a driveway or stall so that a vehicle may be directly driven into the stall and as readily removed therefrom.

My invention further involves a building having superposed floors with zigzag walls and columns supporting the floors the zigzag walls cooperating with other walls or partitions in forming stalls having walls in common with the zigzag wall forming the backbone of all of the stalls. This provides a herring bone arrangement of stalls and with such an arrangement in a garage there may be a maximum capacity in a minimum space.

My invention will be hereinafter more fully described by aid of the drawings, wherein

Figure 1 is a horizontal sectional view of

a building showing diagrammatically an arrangement of stalls;

Fig. 2 is a horizontal sectional view of a portion of one of the floors of a building;

Fig. 3 is a similar view of adjacent floor, and

Fig. 4 is a vertical sectional view of a portion of the building, for instance taken on the line IV—IV of Fig. 3.

In the drawings, I have illustrated a building which may represent a parking building or garage, terminal or other type of building in which vehicles and loaded merchandise may be stored or temporarily placed for safe keeping. The building includes, by the way of an example, outer walls 1 having suitable doorways and windows and between the outer walls are superimposed floors 2 and 3. The floors 2 and 3 are supported relative to one another by rows of zigzag walls 4 and by rows of staggered columns 5 and 6 spaced from each side of each zigzag wall.

Between the rows of zigzag walls 4 there are drive-ways or aisles 7 and there may be drive-ways, aisles, ramps or the like at the outer walls 1 of the building, so that a vehicle may drive about on the floor and enter a desired aisle. In some instances there may be elevators for lifting vehicles to a desired floor.

Considering Figs. 2 and 3, it will be noted that the columns 5 and 6 are arranged with all the columns 6 in one row and all of the column 5 in another row with the columns 5 and 6 placed in alinement with one of the angle portions 8 of the zigzag wall, so that the columns 5 and 6 may be connected to each other and to the zigzag wall by partitions or walls 9 and 10 as a continuation of the angular portion 8 of the zigzag wall. This is on one side of the zigzag wall and on the opposite side thereof the column and partitions aline with the other angular portion of the zigzag wall, thus utilizing the angular portions of the zigzag wall in forming the inner or rear walls of two stalls 11 and 12 disposed at a right angle to each other. The stalls 11 at one side of the angular wall will be in overlapped relation and the same is true of the stalls 12 at the opposite side of the wall and with all of the stalls bordering on the driveways and aisles a vehicle may

be directly driven into or out of a stall without any backing or manipulation of the vehicle in the aisle at the entrance of the stall. It is therefore obvious that a drive-way or aisle may have an entrance at one end thereof and an exit at the opposite end, so that the driver of a vehicle can drive in one end of the aisle and direct into a stall. Backing out of the stall into the aisle it is advantageous to drive to the exit end of the aisle.

The columns 5 and 6 or opposed stall walls 9 and 10 may cooperate in supporting overhead doors 13 or other forms of closures 15 for the outer open ends of the stalls 11 and 12, and the doors and walls may be of fire proof material with the zigzag wall preferably thicker or of greater strength than the stall walls or partitions in order to sustain 20 weight on the floor above. The arrangement of the columns is such as to support floors between the zigzag walls and with the column 6 at the sides of an aisle in staggered relation a vehicle can be readily driven into and out 25 of the stalls. By making the stalls on one floor the reverse of stalls on an adjoining floor the weight of vehicles in the stalls is more evenly distributed, especially when the stall walls or partitions 10 are constructed 30 to cooperate with the columns.

While in the drawings there is illustrated a preferred embodiment of my invention, it is to be understood that the arrangement of the stalls and the construction of the building may be varied within the scope of the appended claims.

What I claim is:—

1. A building having a floor, a zigzag wall on said floor, and stall walls extending from

opposite sides of said zigzag wall and providing stalls disposed at an angle to one another.

2. A building as called for in claim 1, wherein there are superposed floors with the zigzag and stall walls connecting said floors.

3. A building having superposed floors, zigzag walls connecting said floors, and stall walls connecting said floors and extending from both sides of said zigzag walls, all of said walls providing stalls with the stalls on one floor the reverse of the stalls on an adjacent floor.

4. A building as called for in claim 3, wherein the stall walls are in each side of each zigzag wall and provide rows of stalls.

5. On a floor, a zigzag wall, and stall walls aligning with angular portions of said zigzag wall at opposite sides of the wall and providing stalls disposed at a right angle to each other.

6. The combination of floors, a zigzag wall between said floors, columns at each side of said wall, and stall walls connecting said columns to said zigzag wall and cooperating therewith in forming stalls disposed at less than a right angle to the general direction of said zigzag wall.

7. Stalls disposed in rows with the rear wall of one stall forming part of the side wall of an adjoining stall.

8. A building having a floor, a zigzag wall on said floor, said wall extending upwardly to a higher level than the floor at both sides thereof.

In testimony whereof I affix my signature.

CHARLES B. LAWTON.
